US0D1022967S

(12) **United States Design Patent** (10) **Patent No.:** **US D1,022,967 S**
(45) **Date of Patent:** **** Apr. 16, 2024**

(54) **EARPHONE**

(71) Applicant: **Ping Hu**, Shenzhen (CN)

(72) Inventor: **Ping Hu**, Shenzhen (CN)

(73) Assignee: **Ping Hu**, Shenzhen (CN)

(**) Term: **15 Years**

(21) Appl. No.: **29/915,440**

(22) Filed: **Oct. 31, 2023**

(30) **Foreign Application Priority Data**

May 4, 2023 (CN) 202330252136.1

(51) **LOC (14) Cl.** **14-01**

(52) **U.S. Cl.**

USPC **D14/223**

(58) **Field of Classification Search**

USPC ... D14/205, 207, 209, 209.1, 217, 221, 223, D14/225; D24/106, 173, 174

(57) **CLAIM**

The ornamental design for an earphone, as shown and described.

DESCRIPTION

FIG. 1 is a front perspective view of an earphone, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 5; and,

FIG. 10 is an enlarged detail view of area 10 in FIG. 5.

The broken lines in the drawings illustrate the portions of the earphone, which form no part of the claimed design.

1 Claim, 10 Drawing Sheets
